UNITED STATES PATENT OFFICE.

LEO JNO. BAYER, OF ST. LOUIS, MISSOURI.

BOILER-CLEANER.

1,115,485.

Specification of Letters Patent.

Patented Nov. 3, 1914.

Application filed August 2, 1913. Serial No. 782,610.

To all whom it may concern:

Be it known that I, LEO JOHN BAYER, citizen of the United States, residing at St. Louis, State of Missouri, have invented certain new and useful Improvements in Boiler-Cleaners, of which the following is a full, clear, and exact description, reference being had to the accompanying drawings, forming a part hereof.

10 My invention has relation to improvements in boiler-cleaners; and it consists in the novel details of construction more fully set forth in the specification and pointed out in the claims.

15 In the drawings, Figure 1 is a vertical middle section of the front end of one form of a conventional fire-tube boiler showing a special form of my invention applied thereto; Fig. 2 is a combined elevation and vertical cross-section on the zig-zag line 2—2 of Fig. 1; Fig. 3 is an enlarged side sectional elevation of the swing or expansion joint to which the jet pipe is attached; Fig. 4 is an enlarged cross-section on the line 4—4 of Fig. 3; Fig. 5 is a sectional detail showing the opening in the flue-cap or door for the passage of the operating stem; Fig. 6 is a combined sectional and elevational detail showing the connection between the operating stem and the rotatable male section of the swing-joint; Fig. 7 is a front elevation of another form of boiler showing a modified form of my invention applied thereto; Fig. 8 is a horizontal section on the line 8—8 of Fig. 7; and Fig. 9 is a vertical section on the line 9—9 of Fig. 7.

The object of my invention is to construct a device suitable for cleaning or removing soot, cinders, ashes and other material usually accumulating on the inside of the flues or tubes of fire-tube boilers, the means employed being in the form of a suitable tubular member or pipe oscillating in front of the discharge ends of the tubes and being provided with nozzles properly distributed to successively direct jets of steam (or equivalent medium) into the series of tubes, said jets traversing the tubes and scouring their inner surfaces of the accumulations referred to. In the present embodiment of my invention such oscillating member is mounted in the smoke-box of the boiler-furnace, this arrangement serving in a measure to dry and superheat the steam before the same is projected into the tubes.

A further object is to so mount the cleaner

as not to interfere with the opening or closing of the flue-cap or smoke-box doors, the cleaner possessing further and other advantages better apparent from a detailed description of the invention which is as follows:

Referring to the drawings, and for the present to Figs. 1 to 6 inclusive, S represents the boiler shell, t the fire-tubes or flues, a the tube-sheet, B the smoke-box or exit flue, and D the horizontally hinged flue-cap or door of the smoke-box as well understood in the art.

Leading from the steam space of the boiler 70 is a steam-supply pipe 1 in the path of which is disposed a control valve V of any approved design, a drip-cock 2 being interposed between the steam supply source and the valve so that the water of condensation 75 may be properly drained before the steam is allowed to pass through the valve-casing to its ultimate point of consumption. A section of the pipe 1 enters the smoke-box B where it is subjected to the heat of the 80 combustion products, the steam being in a measure superheated before its final discharge, the pipe being preferably supported in the smoke-box by a bracket or equivalent member 3. The pipe 1 terminates in the 85 smoke-box in a T 4 the inner end of whose horizontal leg serves as the female section of a swing or "expansion" joint, the male section 5 of which rotates freely in said female, and passes through a stuffing box or 90 gland h. By means of an elbow e the member 5 is coupled to the jet pipe 6 which is closed at its free end, but is provided with properly distributed peripheral teats, nipples or nozzles 7 facing the tube-sheet a and discharging into the discharge ends of the 95 several tubes t with an oscillation of the pipe about the axis of the joint 5. The opposite or outer end of the T 4 is closed by a plug 8 through which and through a terminal stuffing-box h' of which operates a 100 rotatable stem 9 whose inner end is fastened to the spider or perforated disk 10 secured to the inner end of the joint 5. The preferred manner of making the connection is 105 illustrated to best advantage in Figs. 3, 4, 6, the stem 9 being provided with an inner reduced square (or polygonal) portion 9' which is bounded on either side by screw-threaded portions 9'', the portion 9' being 110 received by a corresponding opening in the spider 10, after which lock or jam-nuts n are

passed over the portions 9", 9", and against the spider, thereby completing the connection. To the outer end of the stem 9 is swiveled an extension 11 passing loosely through an opening *o* in the flue-cap D, and oscillatable vertically or in the plane of oscillation of said flue-cap. The outer end of the stem 11 is provided with a removable hand-wheel 12.

10 The operation of the cleaner is substantially as follows:—The axes of the T 4, stem 9, and that of the joint 5 are coincident, the axis of the pipe 6 being disposed at right angles to that of the joint 5, the pipe sweeping in a plane parallel to the plane of the tube-sheet *a* and across the paths of discharges from the tubes *t* into the smoke-box. When the flue-cap D is closed (Fig. 1) the axis of the extension 11 of the stem 9 is coincident with the axis of the member 9, so that if rotation is imparted to the member 11 (through proper manipulation of the hand-wheel 12), a corresponding rotation will be imparted to the stem 9, and joint section 5, and an oscillation or sweep will be imparted to the jet-pipe 6. If previously, the valve V is opened so as to admit dry and superheated steam into the T 4, the fluid will escape in the form of dry steam-jets through the nipples or teats 7, and, with the oscillation of the pipe 6 in proper direction, said jets will be forced successively into the several tubes *t*, the nipples being so distributed that each tube *t* will receive its proper quota of steam as the pipe 6 is swung around in front of the tube-sheet *a*. In the present embodiment of my invention the steam jets are forced against the natural draft through the tubes *t*, but since only a comparatively few tubes are cleaned or "blown" at any one time, the normal draft of the boiler is not materially interfered with. On the contrary it is increased, because the steam escaping from the rear ends of the tubes expands, increasing the combustion, the natural draft thereby being increased toward the flue, or smoke-box B through the tubes not being "blown." The steam jets in traversing the several tubes or flues *t* scour the inner surfaces of the same thus cleaning them of all accumulations of soot, ashes, dirt, cinders and other material.

When occasion arises to gain access to the interior of the smoke-box B, the hand-wheel 12 is removed, and the door D is swung outwardly. The walls of the opening *o* are made tapering so as not to bind with the member 11, the latter by reason of the swivel joint *m* freely responding to the swinging movement of the door (being depressed with the outward swing of the door as shown by dotted position of the parts, Fig. 1) and when the link 11 has slipped out of the opening *o* the door D may be swung outwardly any desired degree (Fig. 1). Features shown but not alluded to are well

known in the art and require no description in the present connection.

In some cases the smoke-box doors (especially where cast iron doors are used) swing in a vertical plane, being hinged about a vertical axis on each side of the smoke-box. Such a modification is shown in Figs. 7 to 9 inclusive where the doors D', D', close over and against the rotatable stem 11'. In this modification the stem 11' need not be provided with a swivel joint such as *m*, the stem 11' being rigid and comprising a single member secured directly to the member 10, a rotation of said member 11' about its axis imparting a sweep to the jet-pipe 6 the same as in the first construction described. In fact, with the exception of the stem 11' and doors D', the modification is identical with the construction illustrated in Figs. 1 to 6 inclusive. Naturally too, the use of vertically swinging side doors such as D' imparts a slightly different vertical longitudinal section to the smoke-box B (compare Figs. 1 and 9). In either case the axis of oscillation of the jet-pipe 6 corresponds to the axis of the swing joint 5, said axis being so disposed and the jet openings 7 so distributed that as the pipe 6 swings or sweeps about said axis, the steam jets (where steam is employed) will be projected through the entire series of tubes *t* and the boiler thoroughly cleaned (Fig. 2). Obviously, I need not restrict myself to, the precise details here shown; neither need the invention be restricted to "tube" boilers, any flue-boiler being herein contemplated. R (Fig. 2) represents a bar by which the valve V may be actuated, being an expedient well understood by the skilled mechanic.

Having described my invention, what I claim is:—

1. In combination with a tube-boiler and smoke-box thereof, a movable flue-cap for the smoke-box, a tubular member permanently mounted in the smoke-box and adapted to sweep in a plane disposed across the path of discharge of the tubes into the smoke-box, means permanently disposed in the path of the combustion products traversing the smoke-box for delivering a cleaning medium to said member, the latter being perforated peripherally to discharge cleaning jets into the several tubes with the sweep of the member in the plane aforesaid, and means operating through the flue-cap for controlling said member from a point outside the smoke-box.

2. In combination with a tube-boiler provided with an exit-flue for the combustion products, a steam-supply pipe having a section thereof permanently disposed in the path of said combustion products, a jet-pipe leading from and communicating with said section and permanently confined in the flue and oscillating in a plane across the dis-

- charge ends of the tubes, a movable flue-cap for the flue, means operating through the flue-cap for controlling said jet-pipe, the latter being provided with perforations 5 adapted to discharge steam into the several tubes with an oscillation of the pipe in either direction,
3. In combination with a tube-boiler and smoke-box thereof, a steam supply-pipe 10 traversing the smoke-box, a hinged flue-cap for the smoke-box, a swinging jet pipe leading from and communicating with the supply-pipe and permanently positioned in the smoke-box and oscillating across the path 15 of discharge of the combustion products from the fire-tubes into the smoke-box, a member for imparting a swinging movement to the jet-pipe, a swiveled extension coupled to said member and responsive to 20 the oscillations of the flue-cap, said extension passing through the flue-cap and being controllable from a point outside of the flue-cap for a closed position of the latter, the jet-pipe being provided with peripheral 25 perforations for projecting the steam into
- the boiler tubes through the discharge ends thereof.
4. In combination with a tube-boiler, a smoke-box having a movable front, a steam supply pipe having a section permanently 30 confined in the smoke-box and terminating in a T opposite the tube-sheet, a hollow rotatable joint member in said T communicating with the supply-pipe, a jet pipe coupled to the joint, and oscillating in a plane par- 35 allel to the tube-sheet and provided with peripheral discharge openings facing the adjacent ends of the tubes, a spider in the joint member, and a rotatable stem secured to the spider and projecting through the 40 movable front of the smoke-box, the axis of the stem being coincident with the axis of the spider and of the joint-member.

In testimony whereof I affix my signature, in presence of two witnesses.

LEO JNO. BAYER.
